(57) **CLAIM**

The ornamental design for a marshmallow confectionery, as shown and described.

DESCRIPTION

The patent or application file contains at least one drawing executed in color. Copies of this patent or patent application publication with color drawing(s) will be provided by the Office upon request and payment of the necessary fee.

1. Marshmallow confectionery

FIG. 1.1 is a front, top and left side perspective view of a marshmallow confectionery showing my new design;

FIG. 1.2 is a front elevation view thereof;

FIG. 1.3 is a top plan view of a first layer of the marshmal-

low confectionery shown separately for ease of illustration;

FIG. 1.4 is a top plan view of a second layer of the marsh-

mallow confectionery shown separately for ease of illustration;

FIG. 1.5 is a top plan view of a third layer of the marsh-

mallow confectionery shown separately for ease of illustration;

FIG. 1.6 is a top plan view of a fourth layer of the marsh-

mallow confectionery shown separately for ease of illustration;

FIG. 1.7 is a bottom plan view of a fifth layer of the marsh-

mallow confectionery shown separately for ease of illustration; and

FIG. 1.8 is a top plan view thereof.

Marshmallow confectionery in the shape of burger.
